UNITED STATES PATENT OFFICE.

ALFRED H. HOADLEY, OF NEW YORK, N. Y.

IGNITION DEVICE.

1,338,625.

Specification of Letters Patent. Patented Apr. 27, 1920.

Application filed May 20, 1918. Serial No. 235,441.

To all whom it may concern:

Be it known that I, ALFRED H. HOADLEY, a citizen of the United States, residing at New York, in the county of New York and State of New York, have invented new and useful Improvements in Ignition Devices, of which the following is a specification.

This invention relates to ignition devices and has for its primary object the provision of a plurality of electrodes in which spark gaps of varying lengths will be constantly produced therebetween and a multiplicity of sparking points provided whereby to enable the device to properly accommodate itself in substantially an automatic manner to varying conditions of an internal combustion engine at all times.

Another object of the invention relates to an improvement in electric ignition devices in which, through an arrangement of the several parts of the device, the liability of mis-firing is materially reduced and in which the electrodes can be adjusted relatively to vary the distance therebetween to suit all given or known requirements.

Another object of the invention resides in the provision of an ignition device in which the principal parts thereof will be of stock formation, capable of being readily assembled at a minimum cost, while producing a device of a highly practical nature, and one which will be positive of action.

With the above and other objects in view which will appear as the nature of the invention is better understood, the same consists in the improved construction and novel arrangements of parts which will herein-after be fully described and particularly pointed out in the claims.

In the accompanying drawings, has been illustrated, a single and preferred form of the invention, it being, however, understood that no limitations are necessarily made to the precise structural details therein exhibited, but that changes, alterations and modifications within the scope of the claims may be resorted to when desired.

Figure 1 is a side view of my improved ignition device.

Fig. 2 is a vertical section therethrough.

Fig. 3 is a section taken on line 3—3 of Fig. 1.

Fig. 4 is a section taken on line 4—4 of Fig. 1, looking in the direction of the arrows.

The ignition device is in the form of a spark plug which consists of a base 5 threaded exteriorly at 6 for connection with the cylinder of an internal combustion engine so that the base of the plug may be 60 operatively arranged within the cylinder of the engine. This base is provided with a substantially straight bore 7 having an internal thread 8 at its lower end and a similar internal thread 9 at its upper end. 65

Through the bore 7 passes an insulator 10 which may be constructed of any suitable well known material. It is provided with a bore 11 and a chamber 12, the latter being in communication with the bore as shown 70 in Fig. 2. The said insulator is provided with a reduced upper portion 13 and a similar reduced lower portion 14, which are spaced apart by the intermediate enlarged section 15 of said insulator. In this manner shoulders 16 and 17 are formed upon the insulator and associated therewith are circular metallic packing rings 18. A bushing 19 is removably connected with the upper reduced portion 13 of the insulator and 80 as illustrated, the thread 20 of said bushing is received by the thread 9 of the base 6, whereby it may be brought with pressure against the packing gasket 18.

An electrode 21 which is in the form of 85 a threaded sleeve 22 is arranged at the base of the device and adjustably associated with the thread 8 in order that it will serve as a seat for the next adjacent packing gasket 18. This electrode and the bushing 19 above 90 mentioned co-operate to hold the insulator operatively associated with the base 6. In other words, the arrangement of the respective parts is such that such parts when assembled, produce a unitary structure. This 95 electrode 21 is provided with depending arms 23 which are spaced apart to produce openings 24 at the sides of said electrode. These arms are connected together by an integral flat disk 25 which is arranged at 100 right angles to the longitudinal axis of the device.

The second electrode is in the form of a stem 26 which is received by the bore 11 of the insulator. It is threaded at its upper 105 end at 27 and at its lower end at 28, the former thread being projected above the portion 13 of the insulator where it is connected with a set nut 29 and a mating jam nut 30 whereby when once a desired adjust- 110

ment of the electrode has been obtained, it may be fixedly maintained in such position. In addition thereto, the said jam nut and the set nut are arranged for connection in an ordinary electric circuit as will be understood. This electrode extends through the chamber 12 and within the chamber it is provided with an integral collar 31 and an asbestos washer 31 which is adapted to contact with a shoulder 32 at the upper end of the mentioned chamber 12 to establish a seated connection.

The thread 28 of the electrode 26 is received in the socket 33 of a sparkling element 34, the same having a head 35 of circular formation which is convexed and arranged to oppose the flat face of the disk 25 of the mating electrode 21. In this manner it will be evident that a multiplicity of sparking points is provided, while at the same time through the convexed formation of the head 35, and the flat formation of the disk 25, sparking gaps of varying lengths will be formed at the point 36 between such instrumentalities. In this manner it is manifest that the device will accommodate itself automatically and in a substantially elastic manner to varying conditions of internal combustion engines. The two electrodes may be adjusted with respect to each other in order that the gap therebetween can be varied at the will of the operator. The sparking element 34 can be adjusted on the thread 28 to suit varying conditions. In the socket of the sparking element is a spring 37 which bears against

the lower end of the stem 26 to hold said element in its adjusted position.

What is claimed as new is:—

1. A spark plug comprising a base, an insulator extending through said base, an electrode connected with said base and extending across the lower end thereof, a second electrode extending through said insulator and having its end toward said first named electrode threaded, and a sparking member threaded upon said second named electrode and adjustable thereon whereby the distance between said sparking member and said first named electrode may be varied, the lower end of said sparking member being closed and convex.

2. A spark plug comprising a base, an insulator extending through said base, an electrode connected with the lower end of said base and having a portion extending transversely with respect to the axis of the plug, a second electrode extending through said insulator, a sparkling member having an internally-threaded bore engaging upon the end of said second named electrode, and a spring disposed within said bore and bearing against the end wall thereof and against the end of said second named electrode, said sparking member being adjustable longitudinally of said second named electrode whereby to vary the length of the gap between said sparking member and the transverse portion of said first named electrode.

In testimony whereof I affix my signature.

ALFRED H. HOADLEY.
